UNITED STATES PATENT OFFICE.

THEODORE G. SELLECK, OF CHICAGO, ILLINOIS, ASSIGNOR OF ONE-HALF TO JOHN L. DEPPEN, OF CHICAGO, ILLINOIS.

TOOL-HANDLE FASTENING.

1,157,593.

Specification of Letters Patent.

Patented Oct. 19, 1915.

Application filed January 5, 1914, Serial No. 810,436. Renewed March 17, 1915. Serial No. 15,054.

To all whom it may concern:

Be it known that I, THEODORE G. SELLECK, a citizen of the United States, residing at Chicago, in the county of Cook and State of Illinois, have invented certain new and useful Improvements in Tool-Handle Fastenings, of which the following is a specification.

This invention relates to fastenings for retaining tools in socket-handles, and its object is to provide a novel and improved fastening whereby the tool will be securely held in the socket.

The herein stated object is attained by means of a combination and arrangement of parts to be hereinafter described and claimed, and in order that the invention may be better understood, reference is had to the accompanying drawing, in which—

20 Figure 1 is an elevation of the tool and its handle; Fig. 2 is a longitudinal section on the line 2—2 of Fig. 1; Fig. 3 is an end view of the handle-socket, and Fig. 4 is a cross-section on the line 4—4 of Fig. 1.

25 Referring specifically to the drawing, 5 denotes a chisel or other tool which is to be secured in a handle-socket 6. The shank of the tool has a base portion 7 from which extends a tang 8, the outer end of which is reduced or stepped to semicircular form, as indicated at 9. The wall of the socket at that end into which the tang is inserted is thickened, as indicated at 10, and formed with a shoulder 11, against which the shoulder formed by the base 7 squarely abuts, and the side of the base is beveled, as indicated at 12, to produce a taper. In front of the shoulder 11 the socket is flared, the wall thereof being beveled on the inside to correspond to the bevel 12. Thus, the base portion of the shank fits snugly in the socket, but it is prevented from being tightly wedged therein by the shoulder 11.

40 The wall 10 of the socket is internally 45 screw-threaded to receive and hold a sleeve 13, the same being flush at one end with the shoulder 11, and abutting against the base portion 7 of the tool-shank. The inside di-

ameter of this sleeve is such that the tang 8 may be inserted thereinto with a snug fit. 50 The rear end of the sleeve has an opening 14 corresponding in shape to the reduced portion 9 of the tang, the same seating in the opening, whereby the tang is held against rotary motion in the sleeve. 55

Behind the part 10 the sleeve 13 is spaced from the wall of the socket and carries a flat spring 15 secured at one end to the outside of the sleeve, as indicated at 16. The spring extends in a curve partly around the 60 sleeve, and carries at its free end a segmental latch 17 slidably mounted in a cross slot 18 in the sleeve and adapted to be seated in a transverse groove 19 in the tang 8. The latch has a stem 20 to which the free end of 65 the spring is made fast, and said stem screws into a knob or finger-piece 21 seating in a transverse slot 22 in the wall of the socket. The latch is beveled to snap into the groove 19. The spring 15 holds the latch 17 seated 70 in the groove 19, and with the latch in this position the tang 8 is securely locked against longitudinal movement in the sleeve 13. To release the tang, the knob 21 is pressed sideways toward one end of the slot 22, whereupon the latch rises out of the groove 19, as shown by dotted lines in Fig. 4, and when it clears the tang, the tool may be removed. There is sufficient space in the socket to accommodate the spring. The sleeve 13 is 80 mounted in place by being inserted into the socket from the rear end thereof, the opening 14 affording a hold for a screw-driver for screwing the sleeve into place. 85

I claim:

The combination with a handle-socket having a cross slot; of a tool having a tang provided with a transverse groove, a sleeve mounted in the handle-socket and receiving the grooved portion of the tang, said sleeve having a portion which is spaced from the wall of the socket and provided with a cross slot registering with the first-mentioned cross slot and the groove of the tang, means for holding the tang against rotary movement in the sleeve, a latch slidable in the 90 95

cross slot of the sleeve and engageable with the transverse groove of the tang, a finger-piece attached to the latch and passing through the cross slot of the handle-socket 5 to the outside of the latter, and a spring made fast at one end to that portion of the sleeve which is spaced from the wall of the handle-socket, said spring encircling the

sleeve externally and having its free end connected to the latch.

10

In testimony whereof I affix my signature in presence of two witnesses.

THEODORE G. SELLECK.
